CAR DOOR

Filed Jan. 29, 1921

Inventor:
Herman C. Priebe
B. L. Clegg Atty

UNITED STATES PATENT OFFICE.

HERMAN C. PRIEBE, OF BLUE ISLAND, ILLINOIS.

CAR DOOR.

Application filed January 29, 1921. Serial No. 440,989.

To all whom it may concern:

Be it known that I, HERMAN C. PRIEBE, a citizen of the United States, residing at Blue Island, in the county of Cook and State 5 of Illinois, have invented a certain new and useful Improvement in Car Doors, of which the following is a full, clear, concise, and exact description.

My invention relates to doors which are 10 bodily movable in their own planes such as are employed, for example, in the sides of freight cars.

In practicing my invention I employ mechanism for forcing the bodily movement 15 of the door in its own plane comprising one element in the form of a lever that carries a cam member and an element constituting a cam member complementary to the aforesaid cam member, one of these elements being 20 carried by the door and the other being mounted apart from the door upon one side thereof, the movement of the lever forcing movement of the door through the intermediation of the co-operating cam members.

In the preferred embodiment of the invention the cam member upon the lever is produced by means of a slot inclined with respect to the lever, the complementary cam member being in the form of a post receivable 25 in this slot, the swinging movement of the lever resulting in the travel of the post in said slot to open or close the door.

I will explain my invention more fully by reference to the accompanying drawing 30 showing the preferred embodiment thereof and in which Fig. 1 illustrates a portion of a freight car in side elevation having a single door, and provided with a door opening and closing device of my invention, the door being shown in closed position; Fig. 2 is a perspective view of the co-operating cam members of the door opening and closing device of my invention; Fig. 3 is a sectional view on line 3—3 of Fig. 1; Fig. 4 is a sectional view on line 4—4 of Fig. 1; and Fig. 45 5 is a sectional view on line 5—5 of Fig. 1.

Like parts are indicated by similar characters of reference throughout the different figures.

I have shown in the drawing a portion of a single door 1 but it is obvious that my invention is not to be limited to the use thereof in connection with a single door. This door is provided, as usual, with rollers upon its upper end, not shown, that roll upon a door supporting track, also not shown, which

is mounted upon the adjacent side of the freight car 2. The manner of suspending such a freight car door so that it may bodily travel in its own plane is so well known to those skilled in the art as to require no illustration and no further description.

When the door is in position to close the door opening in the side of the car one upright meeting edge thereof engages a face 60 of the upright angle rail 3. This angle rail carries ears 4 and 5 which overlie the outer face of the door to hold it close to the side of the car. The door opening lever 6 is preferably mounted apart from the door 65 upon one side thereof, this lever being desirably pivoted at its upper end to the ear 4. The post 7 that co-operates with the lever is consequently mounted upon the door. The lever 6 has a lateral enlargement or wing 8 70 that is formed with a slot 9 inclined to the lever whereby the portion 8 of the lever is formed into a cam member. The post 7 is receivable in this slot and constitutes a complementary cam member. When the lever is 75 swung the post 7 will travel in the cam slot 9 and will then co-operate with the cam member 8 to effect the bodily movement of the door in its own plane.

In the preferred embodiment of the invention the post is formed with an elongated head 10 extending upon both sides thereof. This head is of such a size and is so disposed that it will be in registry with the slot 9 when the door is sufficiently 80 opened, this head then being capable of being passed through said slot either to bring the post into or out of the slot. When the post is within the slot and the lever is placed in a vertical position the door will be closed 85 and the head of the post will be inclined with respect to said slot so as to overhang the cam member portion 8 of the lever 6 in the region of the slot to prevent separation of the lever and post when the door is in a closed position whereby the lever is enabled to take part in holding the door closed. The head of the post serves to keep the lever in its own plane in which it may be further held by means of the hook 11 that is provided upon the lever and the eye 12 passing through the opening 13 in the lever and through which the free end of the hook is also projected. The hook may be provided with an apertured ear 14 to enable a sealing wire 15 to be assembled with the hook after the free end thereof has been passed through 90 95 100 105 110

the eye 12, the ends of the wire having any usual or suitable car seal applied thereto.

Reference may be had to my co-pending application Serial No. 440,988, filed January 5 29, 1921.

While I have herein shown and particularly described the preferred embodiment of the invention I do not wish to be limited to the precise details of construction shown as 10 changes may readily be made without departing from the spirit of my invention, but having thus described my invention I claim as new and desire to secure by Letters Patent the following:—

- 15 1. The combination with a door mounted to move bodily substantially in its plane; of mechanism for forcing the bodily movement of the door comprising one element in the form of a lever that carries a cam member 20 and an element constituting a cam member complementary to the aforesaid cam member, one of these elements being carried by the door and the other being mounted apart from the door upon one side thereof, the 25 movement of the lever forcing movement of the door through the intermediation of the co-operating cam members, the cam member that is complementary to the cam member carried by the lever overhanging the latter cam member when the door is in closed 30 position then to prevent separation of these cam members, the cam members being relatively formed to permit their separation and the subsequent independent movement of the 35 lever when the door is sufficiently opened.
2. The combination with a door mounted to move bodily substantially in its plane; of mechanism for forcing the bodily movement of the door comprising one element in the 40 form of a lever having a slot inclined with respect thereto and another element in the form of a post receivable in said slot, one of these elements being carried by the door and the other being mounted apart from the

door upon one side thereof, the slotted portion of the lever and said post co-operating to effect bodily movement of the door when the lever is swung, said post having a head which overlies a portion of the lever margining its slot when the door is closed. 45

3. The combination with a door mounted to move bodily substantially in its plane; of mechanism for forcing the bodily movement of the door comprising one element in the form of a lever having a slot and another element in the form of a post receivable in said slot, one of these elements being carried by the door and the other being mounted apart from the door upon one side thereof, the slotted portion of the lever and said post co-operating to effect bodily movement of the door when the lever is swung, said post having a head which overlies a portion of the lever margining its slot when the door is closed. 50

4. The combination with a door mounted to move bodily substantially in its plane; of mechanism for forcing the bodily movement of the door comprising one element in the form of a lever having a slot and another element in the form of a post receivable in said slot, one of these elements being carried by the door and the other being mounted apart from the door upon one side thereof, the slotted portion of the lever and said post co-operating to effect bodily movement of the door when the lever is swung, said post having a head which is inclined with respect to said slot, when the door is closed, then to overhang the slotted portion of the lever 55 and which head is of a size and location to bring it into registry with said slot and enable it to be passed therethrough when the door is sufficiently opened. 60

In witness whereof, I hereunto subscribe my name this twenty-first day of January 70 A. D., 1921.

HERMAN C. PRIEBE.
